Allen & Peck, ATTORNEYS.

UNITED STATES PATENT OFFICE.

LOTTIE M. PECK, OF BRAINTREE, MASSACHUSETTS.

EDGE-TRIMMING MACHINE.

1,300,642.

Specification of Letters Patent. Patented Apr. 15, 1919.

Application filed August 15, 1918. Serial No. 250,046.

To all whom it may concern:

Be it known that I, LOTTIE M. PECK, a citizen of the United States, residing at Braintree, in the county of Norfolk, in the 5 State of Massachusetts, have invented a certain new and useful Improvement in Edge-Trimming Machines, of which the following is a specification, reference being had to the accompanying drawings.

10 The object of this invention is to provide means for rapidly and accurately trimming the linings of shoes and more particularly that portion of such linings which is to be trimmed into parallel relation to those portions of the uppers where the buttons or studs, as the case may be, are to be located. In thus trimming the lining it is desirable and customary to trim slightly back from the edge of the upper and this has been a particularly awkward and uncertain operation because of the fact that the upper lies on top of and hides the lining from view during the trimming operation. My present improvement provides a novel construction 20 of undercutting knife and gage which automatically locates the cut edge of the lining a given distance back from the edge of the upper.

In order to explain my invention clearly 30 I have provided the annexed drawings, in which Figure 1 is a plan view of a machine work table having mounted thereon a cutting tool embodying my present improvement, and also showing, as in the act of being trimmed a section of lining and superposed leather upper. Fig. 2 is an under side plan of the said improved tool.

Fig. 3 is an edge view of the work table and of the work mounted and of said tool, 40 and in Fig. 4 I have shown the said tool in perspective.

Referring to these drawings the letter *a* indicates a portion of the work-supporting table of an edge-trimming machine. *b* denotes a portion of a leather upper and *c* a piece of partly trimmed cloth lining underlying said upper. Secured to the table *a* by means of a fulcrum screw or bolt *d* is an arm *e* which is given a rapid vibratory 50 movement (as indicated by dotted lines in

Fig. 1), by means of an arm *g* which carries a stud *h* that extends up through an opening in the table *a* into a slot *e'* in the arm *e*. Secured to the other end of the arm *e* is a blade *i* whose outer or free end is turned 55 down as at *i'* and notched as at *i''* to provide a knife whose cutting edge lies in a plane at a right angle to the plane of the arm *e*.

Mounted on the knife blade *i* is a gage 60 plate *k* which is secured in place, as here shown, by a clamp screw *m* which extends through an elongated slot *k'*, the arrangement of the gage plate and blade *i* being such that the gage may be adjusted longitudinally on the said plate, within the limits of the slot *k'*.

When it is desired to use my described trimmer the gage is first adjusted on the knife blade so that the outer end of the gage 70 is slightly back from the knife edge *i''* (see Figs. 3 and 4). The arm *e* is started into action thus causing the knife to be vibrated rapidly and the work to be trimmed is placed in position on the work table, with 75 the outlining edge of the leather *b* abutting the end of the gage. As the combined upper and lining *c* are fed forward, the vibrating knife *i''*, which extends slightly underneath the leather upper, engages and trims the said 80 lining, as will be best understood by reference to Fig. 1 of the drawings, the cut edge of the lining being located automatically and accurately by reason of the coöperative relation of the gage with the knife. 85

Having thus described my invention, I claim as new and wish to secure by Letters Patent:

1. The improvement in edge-trimming machines which consists, in combination with a 90 reciprocating arm, of a right-angled knife blade carried by said arm, and a gage mounted upon said blade.

2. The improvement in edge-trimming machines which consists, in combination with a 95 reciprocating arm, of a right-angled knife blade carried by said arm, and a gage adjustably mounted upon said blade.

LOTTIE M. PECK.
